US0D1031900S

(12) **United States Design Patent** (10) **Patent No.:** **US D1,031,900 S**
(45) **Date of Patent:** **** Jun. 18, 2024**

(54) **COLLAPSIBLE STOCK**

(71) Applicant: **VK Integrated Systems, Inc.**,
Fullerton, CA (US)

(72) Inventors: **Steve I. Aguilar**, Fullerton, CA (US);
Vasilios K. Kapogianis, Fullerton, CA (US)

(73) Assignee: **VK Integrated Systems, Inc.**,
Clarksville, TN (US)

(**) Term: **15 Years**

(21) Appl. No.: **29/749,244**

(22) Filed: **Sep. 3, 2020**

(51) LOC (14) Cl. **22-01**

(52) U.S. Cl.

USPC **D22/108**; D22/111

(58) **Field of Classification Search**

USPC D22/104, 105, 108, 111; D21/573, 574
CPC F41C 3/00; F41C 7/00; F41C 23/00; F41C
23/06; F41C 23/08

(74) *Attorney, Agent, or Firm* — Paul J. Backofen, Esq.

(57) **CLAIM**

The ornamental design for a collapsible stock, as shown and described.

DESCRIPTION

FIG. 1 is a right-front perspective view of a collapsible stock showing our new design.

FIG. 2 is a left-rear perspective view thereof.

FIG. 3 is a left side elevation view thereof.

FIG. 4 is a right side elevation view thereof.

FIG. 5 is a top elevation view thereof.

FIG. 6 is a bottom elevation view thereof.

FIG. 7 is a front plan view thereof; and,

FIG. 8 is a rear plan view thereof.

“VK® SYS” is a registered trademark of VK Integrated Systems, Inc.

“SIOS-C” is a registered trademark of VK Integrated Systems, Inc.

Broken lines in the attached drawings are included for the purpose of illustrating portions of the collapsible stock and form no part of the claimed design.

The identified trademark material forms part of the claimed design.

1 Claim, 8 Drawing Sheets
